RESILIENT SHELL

Alexander Rava, Jersey City, N.J.

Application November 22, 1944, Serial No. 564,701

9 Claims. (Cl. 137—156)

1

This invention relates to resilient shells, and more particularly to resilient metallic shells suitable for compressing or pumping elements, motor vessels, vibrating members, for the storage of gases, liquids, or solids, and for many other uses.

While the novel resilient shells of the present invention are suitable for many uses and readily adapt themselves for many purposes, for the purposes of illustration the resilient shells of the present invention will be described more particularly with reference to their use as pumping elements.

Heretofore flexible metallic members have been used for pumping purposes but fatigue failures in the metals of the flexible members have presented serious problems in the practical application of the flexible members. The flexible members heretofore used have usually taken the shape of flat discs, conical diaphragms, or of expandable and contractible corrugated metallic vessels, commonly known as bellows, the flat discs and conical diaphragms being smooth or corrugated concentrically with their axes of symmetry. In the case of flat metallic discs and conical metallic diaphragms when used for pumping purposes their meridional and longitudinal stresses reach the permissible fatigue limits of the metal at practically insignificant deflections and pressure loads even when made of the most suitable metals and alloys. The bellows provide greater life and longer strokes but do not obviate the problem of fatigue failure particularly where relatively rapid operation and relatively large displacements are desired.

Discs and diaphragms, when used for pumping, are subjected to considerable tangential thrusts in concentric regions depending on the magnitude of the central deflections which cause in these longitudinal zones of instability a more or less pronounced tendency to local waving, buckling or folding. This unstable buckling constantly changing its place in the course of the vibratory deflections is one of the main causes of the fatigue of the metallic materials employed and of their local bond-disintegration. Under its persistent action fine cracks are started, either on the surface where minute fine notches and sharp-edged grooves are always present, or within in the bulk of the material itself where minute crystallite or intro-crystallite imperfections are apt to act as powerful stress-raisers. Hence with the aggravation of the local stress-concentrations at the sharp active edges of the widening cracks as a contributing factor, a progressive failure or delayed fatigue rupture is quite probable. Com-

2

parable problems are encountered in the use of bellows.

I have found that thin-walled shells shaped as surfaces of revolution, produced by rotation of plane curves of proper concave contours around the axis of symmetry are excellent for the above stated uses without being subject to the above stated difficulties. Because of thorough symmetry and gradual changes in curvature and because the loading involved is symmetrical to the axis, any unbalanced strains and local excessive bending stresses are efficiently avoided. The exclusion of any permanent deformations and the proper consideration of fatigue limits I have found further require that the cyclically recurrent mechanical deformations of the thin-walled resilient shell or chamber piston should be of a substantially inextensive nature. This requires proper free meridional length in relation to the size of the linear stroke employed and provision for suitable longitudinal resilient extension. I have found that smooth walled shells cannot meet these requirements unless of excessive size and to overcome this difficulty I have discovered an effective structure in which the walls of the shells are corrugated with a plurality of equidistantly disposed meridional corrugations having their maximum dimensions at the equator and tapering down toward each pole of the shell. Such a construction as this provides ample longitudinal resilient extension where needed to offset excessive longitudinal stresses; provides an increased sturdiness and eliminates any compressional strains or thrusts in a longitudinal direction, thus precluding any equatorial buckling.

Among the surfaces of revolution I have found the oblate elasticoid, the oblate ellipsoid with an axes ratio of 1:2, the prolate ellipsoid and the toroid suitable for the above described uses and having inherent properties to best resist the above described stresses.

It is accordingly an object of my invention to provide a novel resilient shell suitable for pumping purposes or for the storage of gases, liquids, or solids.

Another object of my invention is to provide a novel resilient shell in which fatigue failures of the metallic materials employed are overcome.

Another object of my invention is to provide a novel resilient shell in which the meridional and longitudinal stresses do not approach the fatigue limit of the metallic materials employed in the range of deflections and pressure loads usually encountered.

Another object of my invention is to provide

a novel resilient shell in which tangential thrusts are reduced to preclude local wavy buckling.

Another object of this invention is to provide a novel resilient shell in which local bond-disintegration of the metallic material is precluded.

Another object of this invention is to provide a novel resilient shell shaped as a surface of revolution produced by rotation of plane curves of proper concave contours rotated about the axis of symmetry capable of resisting unbalanced strains and local excessive bending stresses.

Another object of this invention is to provide a novel resilient shell shaped as a surface of revolution produced by rotation of plane curves of proper concave contours rotated about the axis of symmetry and meridionally corrugated capable of resisting unbalanced strains and local excessive bending stresses.

Another object of this invention is to provide a novel resilient shell shaped as a surface of revolution produced by rotation of plane curves of proper concave contours rotated about the axis of symmetry and meridionally and equidistantly corrugated with corrugations tapering toward the poles and having their greatest dimension at the equator to preclude any equatorial buckling.

Another object of my invention is to provide a novel resilient shell which is cheap to manufacture, durable and certain and positive in operation.

Other and further objects of my invention will appear as the description thereof proceeds.

In the attached drawing, one embodiment of my novel resilient shell is shown for the purpose of illustration only, and should not be construed as a limitation of the present invention, reference being had to the appended claims to determine the scope of the present invention.

In the attached drawing,

Figure 1 is a top view of an oblate elasticoid showing the meridional corrugations; and

Figure 2 is a perspective view of the oblate elasticoid of Figure 1.

In these figures, in which like reference characters indicate similar parts, there is shown an oblate elasticoid. An oblate elasticoid is a surface of revolution traced by a particular Euler's "elastica" in which the sides of each curve branch are perpendicular to the axis of symmetry, the curve having points of inflection at these intersections. The ratio of the axes of the oblate elasticoid is constant and equal to 1.669254 and the ratio of its radii of the latitudinal and meridional curvatures at any chosen point of its surface is also constant and equal to 2, resulting in a disappearance of any longitudinal static or membrane stresses when the elasticoidal shell is subjected to an internal pressure. This fact, especially advantageous for selecting the oblate elasticoid as the shape of the deformed shell at the end of the pump stroke, cannot be utilized because for a given length of the meridional perimeter the shape of the oblate elasticoid of revolution has the maximum volume among all other possible shapes of solids of revolution, which, at the comparatively small strokes required at a substantially inextensible deformation, results in a smaller volume at the end of the stroke than at the beginning of the same. However, due to the same geometrical property of the maximum volume a greater positive volume displacement is had by using the oblate elasticoid as the shape of the resilient shell at the beginning of the stroke instead of at the end of the stroke. In these figures 10 represents

the surface of a suitable oblate elasticoid having an axis of symmetry 11—11. The surface 10 of the elasticoid is suitably corrugated in a plurality of equidistant meridional corrugations 12 having their largest dimension at the equator 13 of the oblate elasticoid and tapering down toward each pole 14 of the oblate elasticoid to their smallest dimension as at 15, a band of uncorrugated metal 16 being left symmetrically about each pole 14 for clamping purposes and cut away circularly about poles 14 and 17 to receive the actuating members not shown.

As an example of suitable relative dimensions and characteristics for a resilient shell made of Cr-Si-Steel having the shape of an oblate elasticoid of revolution and suitably corrugated as above described, the following dimensions and characteristics are given:

- Minor axis—7.353482 cm.
 20 Major axis—12.2748 cm.
 Wall thickness—0.01524 cm.=0.006"
 Diameter of the cut away portion 17—6.039 cm.
 Circumference of the clamped portion 16—18.9735 cm.
 25 Axial distance between the clamped portions 16 of the shell at the beginning of the stroke—6.85982 cm.
 Over-all (equatorial) diameter of the shell at the beginning of the stroke—12.2748 cm.=4.832"
 30 Circumference of the shell at the equator at the beginning of the stroke—38.5624 cm.
 Free meridional length of the shell— 2×10.017 cm.
 Number of meridional corrugations—100;
 35 Depth of the meridional corrugations—0.1 cm. constant;
 Maximum width of each corrugation at the equator—0.3856 cm.
 Width of each corrugation at the boundary of the clamped portion 16—0.1897 cm.
 40 Maximum cross-sectional moment of inertia of a single meridional strip— 8.37×10^{-6} cm.
 Minimum cross-sectional moment of inertia of a single meridional strip— 4.97×10^{-6} cm.
 Assumed stroke—0.4 cm.
 45 Thrust required for the stroke of 0.4 cm. (empty shell)—14.592 kgr.
 Assumed thrust—20 kgr. (for the empty shell);
 Power required to run the empty shell at 500 strokes of 0.4 cm. per minute—0.00444 metric
 50 H. P. or 0.00438 H. P.
 Assumed power required to run the empty shell at 500 strokes of 0.4 cm. per minute— $1/100$ H. P.;
 Horizontal equatorial deflection of the shell at the end of the stroke— 2×0.1365 cm.
 55 Over-all (equatorial) diameter of the shell at the end of the stroke—12.5478 cm.=4.94"
 Circumference of the shell at the equator at the end of the stroke—39.42 cm.
 Increase of the equatorial circumference at the
 60 end of the stroke—0.8576 cm.
 Volume of the clamped (cylindrical) portion of the shell at the beginning of the stroke— $v_{cc}=196.52$ cub. cm.
 Volume of the ring portion of the shell at the beginning of the stroke— $v_{rc}=429.8$ cub. cm.
 65 Total volume at the beginning of the stroke— $v_{tc}=v_{cc}+v_{rc}=626.3$ cub. cm.
 Volume of the clamped (cylindrical) portion of the shell at the end of the stroke— $v_{ce}=185.06$ cub. cm.
 70 Volume of the ring portion of the shell at the end of the stroke— $v_{re}=436.7$ cub. cm.
 Total volume at the end of the stroke— $v_{te}=v_{ce}+v_{re}=621.76$ cub. cm.
 75 Delivery per stroke— $D=v_{tc}-v_{te}=4.54$ cub. cm.

Assumed volumetric efficiency—0.8
Actual delivery per stroke
 $D_{act} = 4.54 \times 0.8 = 3.632$ cub. cm.

$R_{dm} = 1800$ cub. cm./min.

Location of the maximum tensile stress—at the clamped boundary of the shell;

Direction of this maximum stress—meridional;

Maximum tensile stress— $k_{m_{max}} = 350.15 \times$ internal pressure in kgr./sq. cm.;

The permissible alternating bending stress for heat-treated Cr-Si-Steel (0.8% Cr, 1.5% Si, 0.65%) is

$$k_{AB}^{n_{in}} = k_{AB}^0 (1 - S_C) (1 - \xi_N) = 7500 (1 - 0.5)$$

$$(1 - 0.62) = 1425 \text{ kgr./sq. cm.}$$

where k_{AB}^0 —denotes the ultimate alternating bending stress of a polished specimen, S_C —the basic safety factor and ξ_N —the notch safety factor (notches, scratches, etc. being some of the main technological hazards). The Copper-2% Bé alloy has approximately the same permissible alternating bending stress. Hence, the shell described above can safely stand at the end of the stroke an internal pressure of about 4 kgr./sq. cm.=56.77 lbs./sq. in.

The delivery rate of the shell may be increased by a slight increase in the stroke or by increasing the number of strokes per minute or by both.

The metals and alloys suitable for the expandable and contractible resilient chamber piston shells just described should be soft and comparatively pliable in the annealed state in order to facilitate the production of the shapes without any appreciable inherent and/or residual stresses and yet be capable, by suitable heat-treatment, of being converted into highly elastic, resilient, hard materials of high tensile strength and fatigue limits with an elastic limit of at least 5000 kgr./sq. cm. Some of the alloy-steels for springs such as Cr-Si-Steel, Cr-Ni-Steel, Mn-Si-Steel, Cr-Ni-Mo-Steel, etc. are suitable as materials for the above described resilient shells. Due to corrosion these metals should be given a protective surface coating of Bakelite, glyptal, etc., or in cases where corrosion may be present stainless steel alloys or non-ferrous alloys should be used such as "K"-Monel with 3.5% Al. or the copper-berillium alloys with 2-2.5% Bé., Cu-Ni-Be., etc. which after proper heat treatment, are exceptionally durable, resilient and tough with high fatigue limits.

I have further found that when the resilient shells of the present invention are in use hard clamping of the shell ends introduces additional forces and bending movements especially when the shell is subjected during deformation to internal pressures. Although it is probable that these supplemental stresses are confined to a narrow zone adjacent the boundary they may in cases of hard clamping be materially increased and produce a pronounced distortion of the shell during operation. I have found that these stresses may be minimized by connecting the shell to the rigid driving parts with a cushioned clamping, using soft or semi-soft washers of fiber, leather, bronze and the like backed with thin resilient metallic washers of steel, spring brass, and the like, and these backed with more solid annular discs so that a gradual change from a comparatively soft cushioning to a full rigidity is assured.

As stated above, other surfaces of revolution produced by plane curves of proper concave contours rotated about the axis of symmetry are

suitable for use as my novel resilient shells and among these was mentioned the toroid. The toroidal shape has some structural advantages in respect to the free meridional length and clamping arrangements. As the differential equations describing the elastic conditions of a strained annular shell permit an exact solution, the deflections and stresses of the toroid shell can thus be determined with a high degree of accuracy.

It is to be expressly understood that the resilient metallic shell of the present invention may be of any suitable size and the illustration hereinbefore given is for the purposes of illustration only. Thus the invention may be embodied in containers of a wide variety of sizes when employed as receptacles for gases, liquids, or solids. Also, when used as a pump or compressor, the size may be selected to conform with the capacity desired. It is also to be understood that the corrugational characteristics of the shells may be varied to suit the varying conditions of use.

It will now be apparent that the present invention provides a novel resilient shell suitable for pumping, storage of gases, liquids, or solids and other purposes, shaped as a surface of revolution of a plane curve of proper concave contour rotated about its axis of symmetry in which fatigue failures of the metal of which it is formed are reduced, in which the meridional and longitudinal stresses do not approach the fatigue limit of the metal in the range of deflection and pressure loads usually encountered, in which tangential stresses are reduced to preclude local wavy buckling, in which local bond-disintegration is precluded, which is capable of resisting unbalanced strains and local excessive bending stresses, and which is meridionally corrugated to preclude equatorial buckling, at the same time being durable, cheap to manufacture, and certain and positive in operation.

In order that my invention may be more clearly understood by those skilled in the art, I have made a mathematical analysis of the forces involved in the operation of an oblate elasticoid. The mathematical treatment is reproduced below, from which it will be seen that the conclusions stated above are justified. I have chosen the oblate elasticoid to illustrate the mathematical treatment because of the importance of this form of my invention.

The introduction of the above-mentioned meridional corrugations, considerably reducing the longitudinal rigidity, results in an important simplification of the elastic shell problem as such, since, with the longitudinal stresses safely disposed of, the influence of any two adjacent meridional strips of the shell on each other, at the axially symmetrical loadings here involved, is greatly suppressed. It is, therefore, permissible, as a first approximation, to regard such meridionally corrugated shells as an agglomeration of a number of thin bars of variable cross-section, curved correspondingly to the meridional shape of the respective shell, thus avoiding the extensive, involved and complicated evaluating determinations of hypergeometric, Bessel's or Fuchs' functions. Comparatively fair approximations of the vertical and the horizontal deflections of the shell due to the thrust during the compression stroke, as well as the extent of the effort needed to effect the stroke-deformation of the empty shell, can thus be determined with a degree of accuracy sufficiently correct for the practical purposes by utilizing the relatively simple strain energy expression applied to the equation of the

chosen meridional curve of the respective shell with the proper consideration of the variable moment of inertia of the individual curved bar cross-section and neglecting any shearing. The determination of the radii of curvature at any chosen point of the given deformed shell results from the fact, that in the case of an inextentional deformation, the measure of the curvature remains constant.

A further simplifying assumption—that of the linear cross-sectional stress distribution, is here also justified, due to the invariably large ratio of the radius of curvature to the wall-thickness of the shell (80 or more).

EVOLUTION OF EQUATIONS PERTAINING TO THE OBLATE ELASTICOID

L. Euler studied in his "De curvis elasticis, methodus inveniendi" (1744) the buckled shapes assumed by an elastic slender rod with free ends subjected to compression along its unbent—stationary—geometrical axis by two equal opposing forces, each applied at a corresponding end. He called them "the elastic curves" and recognized nine different periodical shapes of same, symmetrical in respect to the stationary geometrical axis, depending on the angle φ_0 —under which the individual curve crosses said axis. Because of our particular interest in an oblate form we will consider only that shape of the Euler's "elastic curve" for which the sides of each curve-branch are perpendicular to the stationary axis, that is, for which the angle $\varphi_0=90^\circ$, the curve having points of inflexion at these intersections.

The derivation of the formal equations of the elastic curve has been exhaustively treated by W. Hess ("Ueber das Gyroskop," Mathematische Annalen, vol. 19, 1882, pp. 121–154, and "Ueber die Biegung und Drillung eines unendlich dünnen elastischen Stabes mit zwei gleichen Widerständen, auf dessen freies Ende eine Kraft und ein um die Hauptachse ungleichen Widerstandes drehendes Kraftpaar einwirkt," Mathematische Annalen, vol. 25, 1885, pp. 1–38). We will, therefore, confine ourselves to the interpretation and application of same to our particular problem.

Notations

y —the semi-independent variable, the Y-axis of the Cartesian coordinates being the "stationary geometrical axis" mentioned above;
 x —the dependent variable of the Cartesian coordinates the point of origin of which lies at first in the point of inflexion of the elastic curve;
 s —arc-length of the elastic curve, considered as the independent variable;
 S —arc-length of the branch of the elastic curve between two successive points of inflexion, being the points of intersection of the elastic curve with the Y-axis;
 φ —the angle between the tangent to any chosen point of the elastic curve and the Y-axis;
 φ_0 —the angle between the tangent to the elastic curve at its point of intersection with the Y-axis, being also the tangent at the point of inflexion of the curve; in our case $\varphi_0=90^\circ$;
 $x_{\max}$ —maximum value of the abscissa x ;
 $y_{\max}$ —value of the ordinate y corresponding to the maximum value of x ;
 u —the argument of the elliptic functions;
 m —a constant for the particular elastic curve;
 c —curvature at any chosen point of the elastic curve;

- ρ —radius of curvature at any chosen point of the elastic curve;
 R_m —radius of the meridional curvature at any chosen point of the oblate elasticoid of revolution, traced by a branch of the elastic curve rotated around the Y-axis;
 R_n —radius of the latitudinal curvature at the same point as R_m of the oblate elasticoid of revolution;
10 V_{el} —volume of the oblate elasticoid of revolution, traced by a branch of the elastic curve rotated around the Y-axis;
 V_{ell} —volume of an oblate ellipsoid of revolution;
 A_{el} —surface area of the oblate elasticoid of revolution;
15 A_{ell} —surface area of an oblate ellipsoid of revolution;
 $\text{Si}n am$ —the Jacobian doubly-periodic elliptic function "Sine amplitude";
20 $\text{Co}s am$ —the Jacobian doubly-periodic elliptic function "Cosine amplitude";
 $dn am$ —the Jacobian doubly-periodic elliptic function "delta amplitude";
 zn —the Jacobian "zeta function";
25 K —the complete elliptic integral of the first kind (Legendre);
 K' —the complementary complete elliptic integral of the first kind (Legendre);
 K_{45° —the complete elliptic integral of the first kind for $\varphi_0/2=45^\circ$, which has a numerical value $K_{45^\circ}=1.85407474=K'_{45^\circ}$;
30 E —the complete elliptic integral of the second kind (Legendre);
 E' —the complementary complete elliptic integral of the second kind (Legendre);
35 E_{45° —the complete elliptic integral of the second kind for $\varphi_0/2=45^\circ$, which has a numerical value $E_{45^\circ}=1.3506439=E'_{45^\circ}$;
 k —the modulus of the elliptic functions, which 40 for $\varphi_0=90^\circ$ has a value

$$k_{45^\circ} = \text{Si}n \frac{90^\circ}{2} = \text{Si}n 45^\circ = \sqrt{2}/2 = 0.7071068$$

- S_{ell} —perimeter of the ellipse;
45 a —semi-major axis of the ellipse;
 b —semi-minor axis of the ellipse;
 e —the numerical eccentricity of the ellipse;
 ψ —the angle between the semi-minor axis of the ellipse and the focal radius drawn to the end of same;
50 t_0, t_1, t_2, t_3 , and t_4 —the ordinate spacing values for the numerical evaluation of definite integrals according to the method of Gauss;
 A_0, A_1, A_2, A_3 , and A_4 —the values of constants for the numerical evaluation of definite integrals according to the method of Gauss.
55 y_m —the variable ordinate of the shifted Cartesian system of coordinates, the point of origin of which is moved to correspond to $x=x_{\max}$.

The formal equations of the elastic curve are:

$$\frac{dy}{ds} = \text{Co}s \varphi \quad (1)$$

$$\frac{dx}{ds} = \text{Si}n \varphi \quad (2)$$

$$\text{Co}s \varphi - \text{Co}s \varphi_0 = (1 - \text{Co}s \varphi_0) \cdot \text{Co}^2 am(u+K) \quad (3)$$

$$u = m \cdot s \quad (4)$$

$$c = \sqrt{2 \cdot (1 - \text{Co}s \varphi_0) \cdot m \cdot \text{Co} s am(u+K)} \quad (5)$$

Squaring the Equation 5 we have:

$$c^2 = 2 \cdot (1 - \text{Co}s \varphi_0) \cdot m^2 \cdot \text{Co}^2 am(u+K)$$

or

$$(1 - \text{Co}s \varphi_0) \cdot \text{Co}^2 am(u+K) = \frac{c^2}{2m^2} \quad (6)$$

9

Substituting (6) in (3) gives us:

$$\cos \varphi = \cos \varphi_0 = \frac{c^2}{2m^2} \quad (7)$$

Equation 2 may also be presented as follows:

$$\frac{dx}{ds} = -\frac{d(\cos \varphi - \cos \varphi_0)}{d\varphi} \quad (8)$$

or, considering (7):

$$\frac{dx}{ds} = -\frac{1}{2m^2} \frac{d(c^2)}{d\varphi}$$

$$\frac{dx}{ds} = -\frac{1}{2m^2} \frac{d(c^2)}{ds} \frac{ds}{d\varphi}$$

$$\frac{dx}{ds} = -\frac{1}{2m^2} \cdot 2 \cdot c \cdot \frac{dc}{ds} \frac{ds}{d\varphi}$$

$$\frac{dx}{ds} = -\frac{1}{m^2} \cdot c \cdot \frac{dc}{d\varphi} \frac{ds}{ds} \quad (9)$$

In general, the curvature in a point of a plane curve is:

$$c = \frac{d\varphi}{ds}$$

which, put in (9), will furnish:

$$\frac{dx}{ds} = -\frac{1}{m^2} \cdot c \cdot \frac{1}{c} \frac{dc}{ds}$$

$$\frac{dx}{ds} = -\frac{1}{m^2} \frac{dc}{ds}$$

and, after integration:

$$x = -\frac{c}{m^2} \quad (10)$$

It is in general:

$$\sin \frac{\varphi_0}{2} = \sqrt{\frac{1 - \cos \varphi_0}{2}} \quad (11)$$

or,

$$2 \cdot \sin \frac{\varphi_0}{2} = 2 \cdot \sqrt{\frac{1 - \cos \varphi_0}{2}}$$

$$2 \cdot \sin \frac{\varphi_0}{2} = \sqrt{2(1 - \cos \varphi_0)} \quad (12)$$

Substituting (11) in (5) we have:

$$c = 2 \cdot \sin \frac{\varphi_0}{2} \cdot m \cdot \cos am(u+K)$$

which put in (10) gives us:

$$x = -2 \cdot \sin \frac{\varphi_0}{2} \cdot m \cdot \cos am(u+K) \cdot \frac{1}{m^2}$$

and, because of

$$\sin \frac{\varphi_0}{2} = k$$

$$x = -\frac{2}{m} k \cdot \cos am(u+K) \quad (13)$$

Since in our case $k = 0.7071068$, it is:

$$x = -\frac{1}{m} \cdot 1.414214 \cdot \cos am(u+K_{45^\circ}) \quad (14)$$

Substituting the value of $\cos \varphi$ from (3) into (1) we have:

$$\frac{dy}{ds} = (1 - \cos \varphi_0) \cdot \cos^2 am(u+K) + \cos \varphi_0 \quad (15)$$

10

It is in general:

$$\cos \frac{\varphi_0}{2} = \sqrt{\frac{1 + \cos \varphi_0}{2}}$$

Or

$$2 \cdot \cos^2 \frac{\varphi_0}{2} = 1 + \cos \varphi_0$$

$$\cos \varphi_0 = 2 \cdot \cos^2 \frac{\varphi_0}{2} - 1 \quad (16)$$

With the consideration of Relations 11 and 16 the Equation 15 is transformed into:

$$\frac{dy}{ds} = 2 \cdot \sin^2 \frac{\varphi_0}{2} \cdot \cos^2 am(u+K) + 2 \cdot \cos^2 \frac{\varphi_0}{2} - 1$$

$$15: \frac{dy}{ds} = -1 + 2 \left[\sin^2 \frac{\varphi_0}{2} \cdot \cos^2 am(u+K) + \cos^2 \frac{\varphi_0}{2} \right]$$

Since the modulus:

$$k = \sin \frac{\varphi_0}{2}$$

and the complementary modulus

$$k' = \cos \frac{\varphi_0}{2}$$

we have:

$$\frac{dy}{ds} = -1 + 2 [k^2 \cos^2 am(u+K) + k'^2] \quad (17)$$

The relation between the Jacobian elliptic functions gives us:

$$k^2 \cos^2 am(u+K) + k'^2 = dn^2 am(u+K)$$

Therefore (17) takes the shape:

$$35: \frac{dy}{ds} = -1 + 2 \cdot dn^2 am(u+K)$$

or

$$dy = [-1 + 2 \cdot dn^2 am(u+K)] \cdot ds \quad (18)$$

From Equation 4 we have:

$$ds = du/m$$

hence,

$$45: dy = \frac{1}{m} [-1 + 2 \cdot dn^2 am(u+K)] \cdot du \quad (19)$$

After integrating both sides of the Equation 19 we obtain:

$$50: y = \frac{1}{m} \int [-1 + 2 \cdot dn^2 am(u+K)] \cdot du$$

$$y = \frac{1}{m} [u + 2 \cdot \int dn^2 am(u+K) \cdot du] \quad (20)$$

The theory of the Jacobian elliptic functions furnishes us with:

$$55: \int dn^2 am(u+K) \cdot du = \text{Cam}(u+K) - \text{Cam}K \quad (21)$$

where Cam denotes the incomplete elliptic integral of the second kind (Legendre), so that (20) changes to:

$$60: y = \frac{1}{m} [u + 2 \cdot \{\text{Cam}(u+K) - \text{Cam}K\}] \quad (22)$$

Introduction of the Jacobian zeta function gives us:

$$65: \text{Cam}(u+K) = \frac{E}{K} \cdot (u+K) + \text{zn}(u+K)$$

$$66: \text{Cam}(u+K) = \frac{E}{K} \cdot u + E + \text{zn}(u+K) \quad (23)$$

$$70: \text{Cam}K = \frac{E}{K} \cdot K + \text{zn}K \quad (24)$$

but, since $\text{zn}K = 0$,

$$75: \text{Cam}K = E \quad (24)$$

11

Considering (23) and (24), the Equation 22 will be now:

$$y = \frac{1}{m} \left\{ -u + 2 \cdot \left[\frac{E}{K} u + E + zn(u+K) - E \right] \right\}$$

$$y = \frac{1}{m} \left\{ -u + 2 \cdot \left[\frac{E}{K} u + zn(u+K) \right] \right\} \quad (25)$$

Putting in the numerical values of the complete integrals we have:

$$y = \frac{1}{m} \left\{ -u + 2 \cdot \left[\frac{1.3506439}{1.8540747} u + zn(u+K) \right] \right\}$$

$$y = \frac{1}{m} \{ [2.0.7284733 - 1] \cdot u + 2 \cdot zn(u+K) \}$$

$$y = \frac{1}{m} \{ 0.4569466 \cdot u + 2 \cdot zn(u+K) \} \quad (26)$$

Because the Jacobian doubly-periodic function $\text{Cos am}(u+K)$ has a maximum value for $u=K$

$$\text{Cos am}(u+K)_{u=k} = \text{Cos am}(K+K) = -1$$

the dependent variable x (see the Equation 14) has also for $u=K$ a maximum:

$$x_{\max} = -\frac{1}{m} \cdot 1.414214 \cdot \text{Cos am}(u+K)$$

$$x_{\max} = -\frac{1}{m} \cdot 1.414214 \cdot (-1)$$

$$x_{\max} = \frac{1}{m} \cdot 1.414214 \quad (27)$$

The corresponding value of y is:

$$y_{x=\max} = \frac{1}{m} \left\{ -K + 2 \cdot \frac{E}{K} K + 2 \cdot zn(K+K) \right\}$$

Since the value of the Jacobian zeta-function for $2K$ is 0, we have:

$$y_{x=\max} = \frac{1}{m} \{ 2 \cdot E - K \} \quad (28)$$

or,

$$y_{x=\max} = \frac{1}{m} \{ 0.4569466 \cdot 1.8540747 \}$$

$$y_{x=\max} = \frac{1}{m} \cdot 0.8472131 \quad (29)$$

Because of symmetry of the elastic curve in respect to these coordinates $x_{\max}$ and $y_{x=\max}$, they can be regarded as semi-axes of same, especially when the origin of the Cartesian coordinates is moved to the point corresponding $x_{\max}$. Such transfer changes the Expression 25 as follows:

$$y = \frac{1}{m} \{ 0.8472131 - 0.4569466 \cdot u - 2 \cdot zn(u+K) \} \quad (30)$$

Ratio of the semi-axes of our elastic curve is:

$$\frac{x_{\max}}{y_{x=\max}} = \frac{\frac{1}{m} \cdot 1.414214}{\frac{1}{m} \cdot 0.8472131}$$

$$\frac{x_{\max}}{y_{x=\max}} = 1.669254 \quad (31)$$

We can express now the arc-length S of our elastic line in terms of the semi-axes utilizing the Legendre's relation between the complete elliptic integrals of the first and second kind:

$$K \cdot E' + K' \cdot E - K \cdot K' = \frac{\pi}{2} \quad (32)$$

12

For $k = \text{Sin } 45^\circ = k'$, as it is in our case, there are the following equalities:

$$K = K' \text{ and } E = E'$$

hence,

$$K \cdot E' + K' \cdot E - K \cdot K' = 2 \cdot K \cdot E - K^2 = K \cdot (2 \cdot E - K)$$

and (32) simplifies to:

$$10. \quad K \cdot (2 \cdot E - K) = \frac{\pi}{2} \quad (33)$$

Considering (33) the Equation 28 will be:

$$15. \quad y_{x=\max} = \frac{\pi}{2Km} \quad (34)$$

The half-period of the elastic curve being $u=2K$, we have from Equation 4:

$$20. \quad S = \frac{2 \cdot K}{m} \quad (35)$$

or, with reference to (34):

$$S = \frac{\pi}{y_{x=\max} \cdot m} \cdot \frac{1}{m}$$

$$25. \quad S = \frac{\pi}{y_{x=\max}} \cdot \frac{1}{m^2}$$

and to Equation 27:

$$30. \quad S = \frac{\pi}{y_{x=\max}} \cdot \frac{x_{\max}^2}{4k^3}$$

$$S = \frac{\pi}{2 \cdot y_{x=\max}} \cdot \frac{x_{\max}^2}{2(\sqrt{2}/2)^2}$$

$$S = \frac{x_{\max} \cdot x_{\max} \cdot \pi}{y_{x=\max} \cdot 2} \quad (36)$$

35. Utilizing (31) the Equation 36 may be changed into:

$$S = 2 \cdot y_{x=\max} \cdot \left[\frac{x_{\max}}{2y_{x=\max}} \right]^2 \cdot \pi$$

$$40. \quad S = 2 \cdot y_{x=\max} \cdot \left[\frac{1.669254}{2} \right]^2 \cdot \pi$$

$$S = 2 \cdot y_{x=\max} \cdot 0.696602 \cdot \pi$$

$$S = 4.37688 \cdot y_{x=\max} \quad (37)$$

45. or, again,

$$S = 4.37688 \cdot \frac{x_{\max}}{1.669254}$$

$$S = 2.622059 \cdot x_{\max} \quad (38)$$

50. Let us consider now the oblate elasticoid of revolution traced by our particular elastic curve while rotated around its Y-axis, and express the ratio of radii of the principal curvatures by the elements of the curve, that is the ratio of the radius of the latitudinal—to the radius of the meridional curvature at any chosen point of the oblate elasticoid.

An obvious trigonometric relation gives us:

$$60. \quad R_n = -\frac{x}{\text{Cos } \varphi} \quad (39)$$

and, since

$$65. \quad R_m = \frac{1}{c}$$

and because of Relation 10, we have:

$$66. \quad R_m = -\frac{1}{x \cdot m^2} \quad (40)$$

70. The ratio of (39) and (40) will be:

$$71. \quad \frac{R_n}{R_m} = -\frac{x}{\text{Cos } \varphi} : \left(-\frac{1}{x \cdot m^2} \right)$$

$$75. \quad \frac{R_n}{R_m} = \frac{m^2 \cdot x^2}{\text{Cos } \varphi}$$

13

or, with reference to (13) and (3), in which $\cos \varphi_0 = \cos 90^\circ = 0$,

$$\frac{R_n}{R_m} = \frac{m^2 \cdot 4/m^2 \cdot k^2 \cdot \cos^2 am(u+K)}{\cos^2 am(u+K)}$$

$$\frac{R_n}{R_m} = 4 \cdot k^2$$

$$\frac{R_n}{R_m} = 4 \cdot (\sqrt{2}/2)^2$$

$$\frac{R_n}{R_m} = 2 \quad (41)$$

This constant value of the ratio (41) is the reason for my selection of the oblate elasticoidal shape for thin shell containers subjected to an internal pressure, because of the disappearance of any latitudinal stresses in their walls. Thus, in a container, all surface points of which satisfy the ratio (41), any pair of adjacent elementary meridional strips of the shell are exerting neither pressure, pull, nor bending on each other, but, as counterbalance to the internal pressure, they simply only bear independently and collectively meridionally directed bending stresses.

The volume of our oblate elasticoid of revolution is:

$$V = \pi \cdot \int_{u=0}^{u=2k} x^2 dy$$

or, because of symmetry in respect to $x_{\max}$,

$$V = 2 \cdot \pi \cdot \int_{u=0}^{u=k} x^2 dy \quad (42)$$

Making use of the Equations 20 and 28 we are modifying the Equation 30 as follows:

$$y_n = \frac{1}{m} \cdot (2E - K) + \frac{1}{m} [-u + 2 \int dn^2 am(u+K) \cdot du] \quad (43)$$

Putting in (42) the Expression 13 for x and 43 for y we have:

$$V = 2 \cdot \pi \cdot \int_{u=0}^{u=k} \left[-\frac{2}{m} \cdot k \cdot \cos am(u+K) \right]^2 \cdot d \left\{ [(2E - K) - u + 2 \int dn^2 am(u+K) \cdot du] \right\}$$

or, after performing the indicated differentiation of the expression in [1]:

$$V = \frac{8 \cdot \pi \cdot k^2}{m^3} \int_{u=0}^{u=k} \cos^2 am(u+K) \cdot [2 \cdot dn^2 am(u+K) - 1] \cdot du \quad (44)$$

Now, the relations between Jacobinian functions give us the following:

$$dn^2 am(u+K) = 1 - k^2 \cdot \sin^2 am(u+K) \quad (45)$$

and

$$dn^2 am(u+K) = \cos^2 am(u+K) + k^2 \cdot \sin^2 am(u+K) \quad (46)$$

Adding (45) to (46) we arrive at:

$$2 \cdot dn^2 am(u+K) = 1 + \cos^2 am(u+K) + \sin^2 am(u+K) \cdot (k^2 - k^2) \quad (47)$$

and, since in our case ($k = \sin 45^\circ$), the supplementary modulus $k' = k$, we have:

$$2 \cdot dn^2 am(u+K) = 1 + \cos^2 am(u+K) \quad (48)$$

14

Insertion of (48) in (44) results in:

$$V = \frac{8 \cdot \pi \cdot k^2}{m^3} \int_{u=0}^{u=k} \cos^2 am(u+K) \cdot [1 + \cos^2 am(u+K) - 1] \cdot du$$

$$V = \frac{8 \cdot \pi \cdot k^2}{m^3} \int_{u=0}^{u=k} \cos^4 am(u+K) \cdot du \quad (49)$$

Again, the relations between the Jacobinian functions furnish us with:

$$\cos am(u+K) = -k \cdot \frac{\sin am u}{dn am u}$$

or, since $k' = k = \sin 45^\circ$,

$$\cos am(u+K) = -k \cdot \frac{\sin am u}{dn am u} \quad (50)$$

Therefore, the Equation 49 can be transformed as follows:

$$V = \frac{8 \cdot \pi \cdot k^2}{m^3} \int_{u=0}^{u=k} \left[-k \cdot \frac{\sin am u}{dn am u} \right]^4 \cdot du$$

$$V = \frac{8 \cdot \pi \cdot k^6}{m^3} \int_{u=0}^{u=k} \left[\frac{\sin am u}{dn am u} \right]^4 \cdot du \quad (51)$$

We accomplish the numerical evaluation of the definite integral

$$I = \int_{u=0}^{u=k} \left[\frac{\sin am u}{dn am u} \right]^4 du \quad (52)$$

by utilizing the highly accurate Gauss' method of integration using $n=9$ values of ordinates. For this purpose we make the following substitution for our independent variable u :

$$u = \frac{0+K}{2} + \frac{K-0}{2} \cdot t$$

$$u = \frac{K}{2} \cdot (1+t) \quad (53)$$

The numerical values of (t_0) , (t_1) , $(-t_1)$, $\dots$, etc., needed for the evaluation of (56) are given below:

$$\Phi(t_0) = \Phi(u_0) = \Phi(0.927037) = \left[\frac{\sin am(0.927037)}{dn am(0.927037)} \right]^4 = 5$$

$$\left[\frac{0.76536}{0.84090} \right]^4 = (0.910168)^4 = 0.686255$$

$$A_0 \cdot \Phi(t_0) = 0.330239 \cdot 0.686255 = 0.226628 \quad 10$$

$$\Phi(t_1) = \Phi(u_1) = \Phi(1.227632) = \left[\frac{\sin am(1.227632)}{dn am(1.227632)} \right]^4 =$$

$$\left[\frac{0.897370}{0.772881} \right]^4 = (1.161071)^4 = 1.817335 \quad 15$$

$$\Phi(-t_1) = \Phi(u'_1) = \Phi(0.626442) = \left[\frac{\sin am(0.626442)}{dn am(0.626442)} \right]^4 = \left[\frac{0.570914}{0.914886} \right]^4 = \left(0.624027 \right)^4 = 0.151640 \quad 20$$

$$A_1 \cdot [\Phi(t_1) + \Phi(-t_1)] = 0.312347 \cdot (1.817335 + 0.151640) = 0.312347 \cdot 1.968975 = 0.615003$$

$$\Phi(t_2) = \Phi(u_2) = \Phi(1.495655) = \left[\frac{\sin am(1.495655)}{dn am(1.495655)} \right]^4 = \left[\frac{0.967372}{0.729451} \right]^4 = \left(1.326164 \right)^4 = 3.093064 \quad 25$$

$$\Phi(-t_2) = \Phi(u'_2) = \Phi(0.358419) = \left[\frac{\sin am(0.358419)}{dn am(0.358419)} \right]^4 = \left[\frac{0.347300}{0.969375} \right]^4 = \left(0.358272 \right)^4 = 0.016476 \quad 30$$

$$A_2 \cdot [\Phi(t_2) + \Phi(-t_2)] = 0.260611 \cdot (3.093064 + 0.016476) = 0.260611 \cdot 3.109540 = 0.810380 \quad 35$$

$$\Phi(t_3) = \Phi(u_3) = \Phi(1.702069) = \left[\frac{\sin am(1.702069)}{dn am(1.702069)} \right]^4 = \left[\frac{0.994205}{0.711183} \right]^4 = \left(1.397957 \right)^4 = 3.819226 \quad 40$$

$$\Phi(-t_3) = \Phi(u'_3) = \Phi(0.152005) = \left[\frac{\sin am(0.152005)}{dn am(0.152005)} \right]^4 = \left[\frac{0.151129}{0.994268} \right]^4 = \left(0.152000 \right)^4 = 0.000534 \quad 45$$

$$A_3 \cdot [\Phi(t_3) + \Phi(-t_3)] = 0.180648 \cdot (3.819226 + 0.000534) = 0.180648 \cdot 3.819760 = 0.692506 \quad 50$$

$$\Phi(t_4) = \Phi(u_4) = \Phi(1.824557) = \left[\frac{\sin am(1.824557)}{dn am(1.824557)} \right]^4 = 55 \quad \left[\frac{0.999778}{0.707265} \right]^4 = (1.413583)^4 = 3.992871$$

$$\Phi(-t_4) = \Phi(u'_4) = \Phi(0.029517) = \left[\frac{\sin am(0.029517)}{dn am(0.029517)} \right]^4 = 60 \quad \left[\frac{0.029507}{0.999786} \right]^4 = (0.029513)^4 = 0.000001$$

$$A_4 \cdot [\Phi(t_4) + \Phi(-t_4)] = 0.081274 \cdot (3.992871 + 0.000001) = 0.081274 \cdot 3.992872 = 0.324517 \quad 65$$

Inserting the above computed values into (56) we obtain:

$$+1 \int_{-1}^1 \Phi(t) \cdot dt = 0.226628 + 0.615003 + 0.810380 + 0.692506 + 0.324517$$

$$\int_{-1}^{+1} \Phi(t) \cdot dt = 2.669034 \quad 57$$

20

and, thus the definite integral (54):

$$I = \int_{u=0}^{u=k} \left[\frac{\sin am u}{dn am u} \right]^4 du = \frac{K}{2} \int_{-1}^{+1} \Phi(t) \cdot dt = 0.927037 \cdot 2.669034 = 2.474293 + \text{Err.}$$

The estimated error is less than 0.000005. We can therefor, put:

$$I = 2.474293 \quad 58$$

Insertion of this computed numerical value (58) of the definite integral in (51) results in:

$$V = \frac{8 \cdot \pi \cdot k^6}{m^3} \cdot 2.474293 \quad 59$$

Considering (13), (27) and (28), we obtain:

$$V = 2 \cdot \pi \cdot k^4 \cdot x_{\max}^2 \cdot \frac{y_{x=\max}}{2E-K} \cdot 2.474293$$

$$V = (\pi \cdot x_{\max}^2 \cdot 2 \cdot y_{x=\max}) \cdot \frac{k^4}{2E-K} \cdot 2.474293$$

or, after insertion of the numerical values of the constants:

$$V = (\pi \cdot x_{\max}^2 \cdot 2 \cdot y_{x=\max}) \cdot \frac{0.25}{0.847213} \cdot 2.474293$$

$$V = (\pi \cdot x_{\max}^2 \cdot 2 \cdot y_{x=\max}) \cdot 0.295085 \cdot 2.474293$$

$$V = (\pi \cdot x_{\max}^2 \cdot 2 \cdot y_{x=\max}) \cdot 0.730127 \quad 60$$

We may note here that the expression in the brackets represents the volume of a straight cylinder having a circular base with a radius $x_{\max}$ —the major semi-axis, and a height equal to $2 \cdot y_{x=\max}$ —the minor axis of the oblate elasticoid of revolution.

We have further:

$$V = (x_{\max}^2 \cdot y_{x=\max}) \cdot 2 \cdot \pi \cdot 0.730127 \quad 61$$

$$V = x_{\max}^2 \cdot y_{x=\max} \cdot 4.587523 \quad 62$$

40 The surface of the oblate elasticoid of revolution is:

$$A = 2 \cdot \pi \cdot \int_{u=0}^{u=2k} x \cdot ds \quad 63$$

or, because of symmetry in regard to its major axis:

$$A = 4 \cdot \pi \cdot \int_{u=0}^{u=k} x \cdot ds \quad 64$$

With reference to (13) and (4) we have:

$$A = 4 \cdot \pi \cdot \int_{u=0}^{u=k} -\frac{2}{m} \cdot k \cdot \cos am(u+K) \cdot d(u/m)$$

$$A = \frac{8 \cdot \pi \cdot k^2}{m^2} \int_{u=0}^{u=k} [-\cos am(u+K)] \cdot du$$

Utilizing the relation 50, we obtain:

$$A = \frac{8 \cdot \pi \cdot k}{m^2} \int_{u=0}^{u=k} k \cdot \frac{\sin am u}{dn am u} \cdot du$$

$$A = \frac{8 \cdot \pi \cdot k^2}{m^2} \int_{u=0}^{u=k} \frac{\sin am u}{dn am u} \cdot du \quad 65$$

70 For the numerical evaluation of the definite integral in the Expression 65:

$$J = \int_{u=0}^{u=k} \frac{\sin am u}{dn am u} \cdot du \quad 66$$

21

we apply again the integration method of Gauss using $n=9$ ordinates and the values already obtained.

Thus:

$$J = \frac{K}{2} \int_{-1}^{+1} \theta(t) \cdot dt \quad (67)$$

where

$$\theta(t) = \frac{\sin am u}{dn am u} \quad (68)$$

$$\theta(t_0) = \theta(u_0) = \theta(0.927037) = \frac{\sin am(0.927037)}{dn am(0.927037)} = \frac{0.76536}{0.84090} = 0.910168$$

$$A_0 \cdot \theta(t_0) = 0.330239 \cdot 0.910168 = 0.300573$$

$$\theta(t_1) = \theta(u_1) = \theta(1.227632) = \frac{\sin am(1.227632)}{dn am(1.227632)} = \frac{0.897370}{0.772881} = 1.161071$$

$$\theta(-t_1) = \theta(u'_1) = \theta(0.626442) = \frac{\sin am(0.626442)}{dn am(0.626442)} = \frac{0.570914}{0.914886} = 0.624027$$

$$A_1 \cdot [\theta(t_1) + \theta(-t_1)] = 0.312347 \cdot (1.161071 + 0.624027) = 0.312347 \cdot 1.785098 = 0.557570$$

$$\theta(t_2) = \theta(u_2) = \theta(1.495655) = \frac{\sin am(1.495655)}{dn am(1.495655)} = \frac{0.967372}{0.729451} = 1.326164$$

$$\theta(-t_2) = \theta(u'_2) = \theta(0.358419) = \frac{\sin am(0.358419)}{dn am(0.358419)} = \frac{0.347300}{0.969375} = 0.358272$$

$$A_2 \cdot [\theta(t_2) + \theta(-t_2)] = 0.260611 \cdot (1.326164 + 0.358272) = 0.260611 \cdot 1.684436 = 0.438983$$

$$\theta(t_3) = \theta(u_3) = \theta(1.702069) = \frac{\sin am(1.702069)}{dn am(1.702069)} = \frac{0.994205}{0.711183} = 1.397957$$

$$\theta(-t_3) = \theta(u'_3) = \theta(0.152005) = \frac{\sin am(0.152005)}{dn am(0.152005)} = \frac{0.151129}{0.994268} = 0.152000$$

$$A_3 \cdot [\theta(t_3) + \theta(-t_3)] = 0.180648 \cdot (1.397957 + 0.152000) = 0.180648 \cdot 1.549957 = 0.279997$$

$$\theta(t_4) = \theta(u_4) = \theta(1.824557) = \frac{\sin am(1.824557)}{dn am(1.824557)} = \frac{0.999778}{0.707265} = 1.413583$$

$$\theta(-t_4) = \theta(u'_4) = \theta(0.029517) = \frac{\sin am(0.029517)}{dn am(0.029517)} = \frac{0.029507}{0.999786} = 0.029513$$

$$A_4 \cdot [\theta(t_4) + \theta(-t_4)] = 0.081274 \cdot (1.413583 + 0.029513) = 0.081274 \cdot 1.443096 = 0.117286$$

$$\int_{-1}^{+1} \theta(t) \cdot dt = 0.300573 + 0.557570 + 0.438983 + 0.279997 + 0.117286$$

$$\int_{-1}^{+1} \theta(t) \cdot dt = 1.694408 \quad (69)$$

22

$$J = \int_{u=0}^{+1} \frac{\sin am u}{dn am u} \cdot du = \frac{K}{2} \int_{-1}^{+1} \theta(t) \cdot dt = 0.927037 \cdot 1.694408 + \text{Err}$$

$$J = 1.570779 + \text{Error}$$

The estimated error being less than 0.000002, we can neglect it, and thus put

$$J = 1.570779 \quad (70)$$

Inserting (70) into (65) we arrive at:

$$A = \frac{8 \cdot \pi \cdot k^2}{m^2} \cdot 1.570779 \quad (71)$$

$$A = 4 \cdot \pi \cdot k \cdot (2k/m) \cdot 1/m \cdot 1.570779$$

and considering (13), (27) and (28), we obtain:

$$A = x_{\max} \cdot y_{\max} \cdot \frac{4 \cdot \pi \cdot k}{2E - K} \cdot 1.570779$$

$$A = x_{\max} \cdot y_{\max} \cdot \frac{12.566370 - 0.707107}{0.847213} \cdot 1.570779$$

$$A = x_{\max} \cdot y_{\max} \cdot \frac{8.878697}{0.847213} \cdot 1.570779$$

$$A = x_{\max} \cdot y_{\max} \cdot 10.479888 \cdot 1.570779$$

$$A = x_{\max} \cdot y_{\max} \cdot 16.461588 \quad (72)$$

For comparison we determine the surface area of an oblate ellipsoid of revolution having same axes ratio as our oblate elasticoid, namely

$$a/b = 1.669254 \quad (73)$$

Let f denote here the linear eccentricity:

$$f = \sqrt{a^2 - b^2} = b \cdot \sqrt{a^2/b^2 - 1} \quad (74)$$

then the surface area of the oblate ellipsoid of revolution is:

$$A_{\text{ell.}} = 2 \cdot \pi \cdot a \cdot \left(a + \frac{b^2}{2f} \cdot \ln \frac{a+f}{a-f} \right) \quad (75)$$

$$A_{\text{ell.}} = 2 \cdot \pi \cdot a \cdot b \cdot \left(a/b + \frac{1}{2\sqrt{a^2/b^2 - 1}} \cdot \ln \frac{a/b + \sqrt{a^2/b^2 - 1}}{a/b - \sqrt{a^2/b^2 - 1}} \right) \quad (76)$$

$$(a/b)^2 = (1.669254)^2 = 2.786409$$

$$\sqrt{(a/b)^2 - 1} = \sqrt{2.786409 - 1} = \sqrt{1.786409} = 1.33657$$

$$a/b + \sqrt{(a/b)^2 - 1} = 1.669254 + 1.33657 = 3.005824$$

$$a/b - \sqrt{(a/b)^2 - 1} = 1.669254 - 1.33657 = 0.332684$$

$$\frac{a/b + \sqrt{(a/b)^2 - 1}}{a/b - \sqrt{(a/b)^2 - 1}} = \frac{3.005824}{0.332684} = 9.035072$$

$$\ln 9.035072 = 2.302585 \cdot \lg 9.035072 = 2.302585 \cdot 0.9959316 = 2.293217$$

$$A_{\text{ell.}} = 2 \cdot \pi \cdot a \cdot b \cdot \left(1.669254 + \frac{2.293217}{2.1.33657} \right) =$$

$$2 \cdot \pi \cdot a \cdot b \cdot (1.669254 + 0.857870)$$

$$A_{\text{ell.}} = a \cdot b \cdot 6.283185 \cdot 2.527124$$

$$A_{\text{ell.}} = a \cdot b \cdot 15.878388 \quad (77)$$

The volume of the oblate ellipsoid of revolution having similar semi-axes as our oblate elasticoid is:

$$V_{\text{ell.}} = 4/3 \cdot \pi \cdot a^2 \cdot b \quad (78)$$

$$V_{\text{ell.}} = a^2 \cdot b \cdot 2 \cdot \pi \cdot 0.666667$$

$$V_{\text{ell.}} = a^2 \cdot b \cdot 6.283185 \cdot 0.666667$$

$$V_{\text{ell.}} = a^2 \cdot b \cdot 4.188792 \quad (79)$$

Comparing (79) with (62) we see that the volume of our oblate elasticoid of revolution is larger than the volume of an oblate ellipsoid of revolution with similar axes. Furthermore, we may point out here that for a given length of the meridional perimeter the shape of the oblate elasticoid of revolution has the maximum volume among all other possible shapes of solids of revolution, because the equation of its meridional curve—the elastic line—is the one, which fully 10 satisfies the isoperimetric criteria established by Euler.

For the purpose of practical enumeration of the coordinates x and y of the elastic curve we may simplify the Expressions 13 and 26.

$$y_m = \frac{1}{m} \left\{ 0.8472131 - 0.4569466 \cdot u - 2 \cdot \left[zn(u) - 0.5 \cdot \cos am(u) \cdot \frac{\sin am(u)}{dn am(u)} \right] \right\} \quad (84)$$

$$y_m = \frac{1}{m} \left\{ 0.8472131 - 0.4569466 \cdot u - 2 \cdot zn(u) + \cos am(u) \cdot \frac{\sin am(u)}{dn am(u)} \right\} \quad (85)$$

Utilizing the Relation 50 the Equation 13 changes to:

$$x = -\frac{2}{m} \cdot k \left[-k \cdot \frac{\sin am(u)}{dn am(u)} \right]$$

$$x = \frac{1}{m} \cdot 2 \cdot k^2 \cdot \frac{\sin am(u)}{dn am(u)}$$

but, since

$$k^2 = \sin^2 45^\circ = (\sqrt{2}/2)^2 = 0.5 \quad (80)$$

we have:

$$x = \frac{1}{m} \cdot \frac{\sin am(u)}{dn am(u)} \quad (81)$$

The additional theorem of the Jacobian zeta function:

$$zn(u+v) = zn(u) + zn(v) - k^2 \cdot \sin am(u) \cdot \sin am(v) \cdot \sin am(u+v) \quad (82)$$

gives for $v=K$:

$$zn(u+K) = zn(u) - k^2 \cdot \sin am(u) \cdot \sin am(u+K) \quad (45)$$

1.414214					
0.707107					

but, since:

$$\sin am(u+K) = \frac{\cos am(u)}{dn am(u)} \quad (83)$$

we have:

$$zn(u+K) = zn(u) - k^2 \cdot \sin am(u) \cdot \frac{\cos am(u)}{dn am(u)}$$

$$zn(u+K) = zn(u) - k^2 \cdot \cos am(u) \cdot \frac{\sin am(u)}{dn am(u)}$$

and, considering (80):

$$zn(u+K) = zn(u) - 0.5 \cdot \cos am(u) \cdot \frac{\sin am(u)}{dn am(u)} \quad (84)$$

$$15 \quad \text{Insertion of (84) into (30) results in:}$$

$$s = \frac{1}{c} = -\frac{1}{m^2 x} \quad (86)$$

25 The tangent to any chosen point of the elastic curve forms an angle φ with the Y-axis. It is (see Expressions 3 and 50):

$$\cos \varphi = \cos^2 am(u+K) = k^2 \left[\frac{\sin am(u)}{dn am(u)} \right]^2$$

$$\cos \varphi = 0.5 \left[\frac{\sin am(u)}{dn am(u)} \right]^2 \quad (87)$$

We are given below a table of the numerical values of the Cartesian coordinates of the elastic curve— x and y_m for $m=1$, together with the corresponding values of the radius of curvature ρ , $\cos \varphi$ and the angle φ between the tangent and the Y-axis, for the ascending values of the independent variable u .

40 Next is shown the elastic curve itself drawn to a scale $2.y_x=\max=8.472131''$ or $m=0.2''$, the upper part of the curve showing divisions of $s=0.25''$ corresponding to the ascending steps of $u=0.05$. The circle of curvature, drawn for the apex, is being very closely followed by the curve for quite some length.

To those skilled in the art changes to or modifications of the above described illustrative embodiment of the present invention may now be suggested, without departing from the inventive concept of the present invention, and reference should be had to the appended claims to determine the scope of the present invention.

In the foregoing specification and in the claims I refer to a thin walled shell and give the thickness of such a shell in a particular example. It is to be understood that by a thin walled shell I mean one in which the stresses in the mid-layer of the wall may be neglected for stress analysis purposes as is well understood and is thoroughly explained in works on stress analysis.

What is claimed is:

1. An expandable and contractible resilient motor vessel comprising a meridionally corrugated thin-walled shell of uniform thickness shaped generally as a surface of revolution of Euler's elastica rotated about its axis of symmetry.

2. An expandable and contractible resilient thin-walled vessel of uniform thickness shaped generally as an oblate elasticoid and meridionally corrugated, said elasticoid being formed by the revolution of Euler's elastica curve rotated about an axis of symmetry with the curve perpendicular to said axis at its intersection therewith.

3. An expandable and contractible resilient thin-walled vessel of uniform thickness shaped generally as an oblate elasticoid formed by the revolution of Euler's elastica curve about an axis of revolution and having equidistant meridional corrugations having their greatest dimension at the equator and tapering toward the poles of the oblate elasticoid.

4. An expandable and contractible resilient thin-walled vessel of uniform thickness shaped substantially as an oblate elasticoid, formed by revolution of Euler's elastica curve about an axis of symmetry, and having meridionally extending corrugations over a portion thereof.

5. A vessel as in claim 4 wherein said corrugations extend completely around the equator of said vessel and only partially between the poles thereof.

6. A vessel as in claim 5 wherein said corrugations extend partially between said poles symmetrically about the equator of said vessel.

7. A vessel as in claim 6 wherein said corrugations extend between two equal imaginary circles concentric respectively with said poles.

8. An expandable and contractable resilient thin-walled vessel of uniform thickness shaped substantially as an oblate elasticoid, formed by revolution of Euler's elastica curve about an axis of symmetry, and having meridionally extending corrugations having a depth small in comparison to the equatorial diameter of said vessel and extending around the equator of said vessel, said corrugations being spaced apart by distances small in comparison with the circumference of said vessel on said equator.

9. A vessel as in claim 8 wherein said corrugations are most widely separated at said equator and converge toward the poles of said vessel.
